UNITED STATES PATENT OFFICE.

WILLIAM FREDERICK EMERSON, OF BUFFALO, NEW YORK, ASSIGNOR TO BUFFALO METAL GOODS COMPANY, OF BUFFALO, NEW YORK, A CORPORATION OF NEW YORK.

GREASE-CUP.

1,373,805.

Specification of Letters Patent.

Patented Apr. 5, 1921.

Application filed April 13, 1917. Serial No. 161,890.

To all whom it may concern:

Be it known that I, WILLIAM F. EMERSON, a citizen of the United States, residing at Buffalo, in the county of Erie and State of New York, have invented new and useful Improvements in Grease-Cups, of which the following is a specification.

This invention relates to grease cups for the lubrication of bearings and consists in a simple and compact arrangement and construction particularly adapted for the handling of grease when put up in the form of capsules or protectively inclosed charges of grease contained within a suitable container 10 or wrapper and of a form and size to be received within the cup. A particularly desirable feature of my invention consists in an improved arrangement which greatly facilitates the removal of the emptied containers 15 without handling, thus eliminating danger of soiling the hands.

A desirable embodiment of my invention is shown in the accompanying drawing wherein the reference numerals of this description are applied to the corresponding parts in the several views. Therein Figure 1 is a vertical sectional view showing a desirable form of my invention. Fig. 2 is a similar view showing the parts in advanced 20 position and Fig. 3 is a view showing the parts with the cap removed and the emptied container exposed to be knocked off or otherwise removed.

The approved form of my invention here disclosed consists of a base portion 1 provided with a threaded flange portion 2 adapted to be threaded to a suitable support 3 which may be a journal box or bearing of an automobile or other part which it is desired to lubricate. The base 1 is provided with a central passage 4 for the lubricant communicating with the bearing passage 5 of the support 3 and is provided with the peripheral threads 6 designed to receive 40 thereon the grease cap 7 which is desirably of the standard size as employed in automobile construction and adapted to receive a charge of grease and to feed the same through the passage 4 to the bearing as the 45 cap is screwed down upon its base 1.

In accordance with my invention the grease is contained in a suitable collapsible container 8 which may be of paper and the charge so contained is, as shown, of the

proper size to be received within the cap 7 55 wherein it is placed with its open end 9 corresponding in position to the open end of the cap. In operation the cap is then inserted and screwed onto the base portion 1 and as will be readily understood as the cap is 60 screwed down the grease will be fed into the bearing and the paper container collapses.

To facilitate the removal of the collapsed container I have provided means on the base portion 1 adapted to prevent the crushed 65 container adhering to the inside of the cap when the cap is removed which would necessitate troublesome manipulation to accomplish its removal. The means provided for this purpose as here disclosed consists in 70 forming the base portion with an undercut annular groove 10 positioned whereby a portion of the container will be forced therein under the pressure from the cap in expelling the grease. This effect is indicated in Fig. 75 2 of the drawing and in Fig. 3 the cap is shown removed with the collapsed container retained on the base 1 and exposed in position which permits of its being conveniently removed by merely pushing it off the base 80 which requires no handling of the grease, as is readily understood. As shown the groove 10 may desirably be downwardly inclined more readily to connect with the crushed container for the incline will assist in turning 85 in of the paper into clamping engagement with the base.

It will be understood that many modifications of my invention can be made without departing from the scope thereof and it is 90 therefore intended that all matter contained herein shall be interpreted as illustrative and not in a limiting sense.

Having described my invention I claim,—

1. A grease cup adapted for use with 95 grease in containers, comprising a base portion having a passage therethrough for the grease, a cap adapted for connection with the base and movable relative to the base to feed the grease and means on the base to engage a container to prevent its removal with the cap.

2. In a device for applying the lubricant or grease to bearings and the like, the combination with a grease containing capsule 100 adapted to be collapsed by pressure, said capsule having a closed upper end and an opening in the lower end, of a grease cup 105

comprising a cup or hollow portion to receive the capsule, and a base threaded to fit the cup from below and adapted to abut the lower end of the capsule, said base having a hole for the outflow of the grease and having its upper and inner end formed to engage with and to retain the collapsed capsule after the grease has been expelled.

3. A grease cup adapted for use with grease in containers comprising a base portion having a passage therethrough for the grease, a cap threaded thereto to be movable relative to the base to compress the grease container and said base having a shoulder formed thereon and a groove adjacent the shoulder to engage with the crushed container to retain it on the base on removal of the cap.

4. A grease cup adapted for use with grease in containers comprising a base portion, having a passage therethrough for the grease, means for securing it in position, a cap threaded thereto to be movable relative to the base to compress the grease container and said base having a shoulder formed thereon to be engaged by the crushed container to retain it on the base on removal of the cap, said shoulder being formed by a groove in the base and said groove being inclined to guide the turning in of the container.

5. A grease cup comprising a base having a passage for the outflow of the grease, said base being adapted to be fixed in position adjacent the bearing to be lubricated, a second part movable with relation to the base to force the grease out from a compressible capsule through the passage and to compress the capsule on the base, and means on the base to engage with and retain the capsule when the latter has been compressed.

6. A grease cup for use with a compressible capsule containing grease, comprising a fixed base adapted to be fixed in position adjacent the part to be lubricated and formed with a passage for the outflow of the grease, and a second part arranged to be movable with relation to the base to compress the capsule thereon and to expel the grease from the capsule, said base being

provided with a shoulder and a groove adjacent the shoulder to engage with and retain the compressed capsule.

7. A grease cup comprising a base, a cap threaded to engage with a thread on the base and adapted to be screwed down thereon to expel the grease from a compressible capsule, and means on the upper end of the base for engaging with and retaining the compressed capsule.

8. The combination with a grease cup comprising a base having a small outlet passage for the lubricant and a cap threaded to fit the base, of a compressible grease capsule containing lubricant arranged within the cap and adapted to be compressed between the cap and the base, as the former is turned down on the latter, said capsule having a closed end and an open end arranged adjacent the base, and means on the upper end of the base to engage with the margin of the crushed capsule at its open end and retain the capsule when the cap is withdrawn.

9. A two part grease cup, adapted to receive a grease containing capsule of compressible material, comprising a base, a cylindrical cap having an open lower end to admit the upper end of the base and internally threaded to engage with the same, and means on the upper end of the base to engage with and retain the compressed capsule after the grease has been expelled and while the cap is being withdrawn.

10. A grease cup comprising a metal base having a reduced tip externally threaded to engage with the support, a central passage for the delivery of the grease, a circular body externally threaded to receive a cap, a head on the body of smaller diameter than the latter and an inclined groove between the body and the head to receive the edge of the capsule and retain the same when the latter has been compressed, and a cylindrical metal cap having a closed upper end and an open lower end and internally threaded to engage with said body thread.

In testimony whereof I have signed my name to this specification.

WILLIAM FREDERICK EMERSON.
